UNITED STATES PATENT OFFICE.

ANASTASIUS MÄUSEL, OF MAXHÜTTE-HAIDHOF, GERMANY.

ROLLING-MILL FOR MANUFACTURING AND DRESSING OR POLISHING SHEET METAL.

1,198,741.

Specification of Letters Patent. Patented Sept. 19, 1916.

Application filed December 4, 1914. Serial No. 875,407.

To all whom it may concern:

Be it known that I, ANASTASIUS MÄUSEL, a citizen of the German Empire, and resident of Maxhütte-Haidhof, Kingdom of Bavaria, Germany, have invented certain new and useful Improvements in Rolling-Mills for Manufacturing and Dressing or Polishing Sheet Metal, of which the following is a specification.

10 My invention relates to improvements in rolling mills for manufacturing and dressing or polishing sheet metal, and more particularly in the apparatus for feeding the blank from the rear of the roll train to the front side thereof and with its front end between the rolls.

15 The object of the improvements is to provide an apparatus of this class in which a pair of guide rollers are provided one behind the other and at the rear of the rolls, one of which guide rollers is adapted to be shifted toward and away from one of the reducing rolls. Thereby I am enabled to guide short blanks between one of the reducing rolls and the adjacent guide roller, and long blanks between the inner and outer guide rollers. Thereby when rolling thin sheet metal or the like of small length the path of the blank when passing from the 20 rear side to the front side of the reducing rolls is reduced as compared to known constructions. Therefore by means of my improved apparatus blanks of different lengths can be reduced on the same roll train, and the blanks are fed backward to the front side of the roll train along comparatively short paths, so that the economy of the apparatus is high.

25 In the preferred form of the apparatus the feeding mechanism is constructed in such a way, that both guide rollers are simultaneously shiftable. Thereby the guide rollers can be set according to the length of the blank, so that the blanks of different lengths are always fed to the front side of the reducing rolls along the shortest path.

30 In a preferred embodiment of the invention the inner and outer guide rollers are mounted on a common slide which can be set toward and away from the rollers. This construction is preferable because when shifting the slide and simultaneously shifting the inner and outer guide rollers the pressure of the outer guide rollers on the

inner ones remains the same in all the positions of the slide.

35 In order that my invention be more clearly understood several examples embodying the same have been illustrated in the accompanying drawings, in which the same letters of reference have been used in all the views to indicate corresponding parts.

40 In said drawings—Figure 1, is a side view of a rolling mill provided with my improved blank feeding mechanism, Figs. 2 to 4, are 45 vertical sections of rolling mills provided with feeding apparatus of modified constructions. Fig. 5 is a plan view (with parts broken away) of the construction shown in Fig. 2; Figs. 6 and 7 illustrate in sectional 50 elevation and in plan view, respectively, another modification of my invention; and Fig. 8 is a detail elevation of a further modification.

45 In the example shown in Fig. 1 of the drawings a pair of reducing rolls *b* and *c* are mounted in housing frames *a*. At the rear of the upper roll *b* guide rollers *d* and *e* are provided one behind the other. As shown the bearings *f* of the inner guide rollers are shiftably mounted in stationary horizontal guide ways *g* and they are acted upon by springs *h* and a screw-threaded spindle *i*, the spring tending to force the bearings *f* to the left and in opposition to 55 the spindle *i*. The outer guide roller *e* is mounted in bearing blocks *k* which have 60 slideable supports in stationary horizontal guide ways *m*. Springs *n* tend to force the bearing blocks *k* to the left. In order to 65 feed the sheet metal or other blank to the rollers *d* and *e* and from the latter to the upper part of the reducing roll *b* and a guide roller *p* provided above the same, guide plates *r*, *s*, and *t* are provided. The blank 70 which is fed from the upper part of the upper reducing roll *b* downward is guided by a roller *u* and plates *v*.

75 For reducing blanks of great length the guide rollers *d* and *e* are set in the positions 80 shown in Fig. 1, the inner roller *d* being shifted by the spindles *i* to the right and the outer roller *e* being forced by the springs *n* in contact with the roller *d*. Thus 85 the blanks are fed through the feeding apparatus in the direction of the arrows *x* and are carried along by the rollers *d* and *e*. The outer roller *e* is driven by a belt 90

gearing σ . If desired a belt gearing or the like may be provided for rotating the inner roller d as indicated at σ' in Fig. 8. After the blank has been fed between the roll b 5 and the roller p it is fed downward.

For reducing blanks of short length the screw threaded spindles i are turned away from the guide roller d , so that the latter is forced by the springs h in contact with the 10 reducing roll b and out of contact with the guide roller e . Now the short blanks are fed along the path indicated by the arrows y , which path is shorter than that of the long blanks which is indicated by the arrows x , and the short blanks are carried along by the reducing roll b and, where the guide roller d is provided with driving means of its own (Fig. 8), by the said 15 guide roller. For feeding the short blanks plates z are secured to the housing frame a , which plates are removed when rolling long blanks.

The rollers d , e , p , and u may be constructed in the form of hollow cylinders.

20 If desired the springs h may be omitted so that pressure is exerted on both rollers d and e by springs n only, see Fig. 8. In this case when reducing short blanks the roller d is forced in contact with the reducing roll by the springs n and through the intermediary of the roller e , and the roller e is driven in the opposite direction. In this case the guide ways m must extend 25 farther to the left. Instead of providing two guide rollers d and e two groups of adjacent guide rollers may be provided.

30 In some cases the roller u located at the front side of the rolling train may be omitted.

35 In the example shown in Figs. 2 and 5 the reducing rolls 1 and 2 are mounted in the usual way in a housing frame 3. At the front side of the roll train a table 4 is provided which is adapted to receive the blanks to be fed to the rolls. At the rear of the rolls a slide 6 is horizontally shiftable which is supported on brackets 5 secured to the housing frame 3 and which is equipped with two lateral uprights 10 connected with each other by transverse rods 7, 8, and 9. The slide is adapted to be shifted toward and away from the reducing rolls 1 and 2 by means of screw-threaded spindles 11 which engage in internal screw- 40 threads of blocks 12 provided on the brackets 5. At one of their ends the spindles 11 engage in holes made in the uprights 10, and at their opposite ends they carry hand wheels 13.

45 On the slide 6 inner guide rollers 14 and outer guide rollers 15 are mounted which are in the form of disks and are so mounted a certain distance apart and respectively on shafts 16 and 17 that each of the inner rollers 14 cooperates with an outer roller 15. The

50 shaft 16 is mounted in subsidiary slides 18 which are horizontally slideable in guide ways 181 formed in the lateral uprights 10 of the main slide 6, and which are held in contact with stops 20 formed on the uprights 10 by means of springs 19. The shaft 17 is rotatably mounted in subsidiary slides 21 which are horizontally shiftable in guide ways 22 formed in the uprights 10. Each subsidiary slide 21 is engaged at its right 55 by a spring 23 to which a disk 24 is secured. The said disk is engaged by one end of a screw-threaded spindle 25 which is rotatable therein and engages in a screw-threaded bore of a hub 26 of the upright 10. At its opposite end the spindle carries a hand wheel 27.

To the housing frame 3 a transverse member 28 is secured, and the finished blanks slide over the said member away from the 60 reducing rolls. The transverse member is provided with a stripper 29 which is in contact with the lower reducing roll 2. In a notch 30 of the transverse member 28 guide plates 31 in the form of strips are 65 removably mounted. To arms 32 of the transverse member 28 frames 34 are removably secured by means of bolts 33, and the frames 34 carry rollers 35 providing a guide way permitting finished blanks of great length to be 70 removed from the roll train. For receiving short blanks a carriage 36 may be disposed below the slide 6 in lieu of the strips 31 and the frames 34.

To the transverse bar 9 of the main slide 6 blocks 381 (Fig. 5) are secured which provide a support for a rotary shaft 38 disposed below the rollers 14, 15. To the said shaft curved guide members 39 are secured on which guide rollers 37 are mounted. Furthermore the shaft 38 carries an arm 40 which is connected with a hand lever 42 by a link 41. The said hand lever is adapted to be locked in different positions by means of a segment (not shown).

Near the upper roller 1 and slightly below the shaft 38 a shaft 43 is mounted to rock on the housing frame 3, which shaft carries curved guide pieces 44. Furthermore to the shaft 43 an arm 45 is secured which is connected by a link 46 with one arm of a bell crank lever 47 mounted on the housing frame. The other arm of the said bell crank lever is connected by links 48 and 49 with a foot lever 50. The link 49 is provided with holes 51, and through the said holes a pin may be alternately pushed which acts either from above or from below against a stop plate 52 secured to the housing frame. Thereby the guide members 44 can be fixed 110 in different positions.

To the transverse rods 7 and 8 of the main slide 6 curved guide strips 53 and 54 are secured which engage between the rollers 14 and 15 and extend to the upper part 115 120 125 130

of the upper reducing roll 1. The upper guide strips 54 are provided with guide rollers 55. Below the guide strips 53 and near the upper reducing roll 1 curved guide strips 57 are secured to a transverse rod 56 secured to the housing frame, which guide strips carry guide rollers 58.

At the front side of the upper reducing roll 1 curved guide strips 59 are provided. 10 The upper part of the upper reducing roll is engaged by guide rollers 61 provided on a shaft 60, and the front side of the upper reducing roll 1 is engaged by guide rollers 63 mounted on a shaft 62.

15 One end of the shaft 17 carries a belt pulley 641 which is adapted to be rotated by means of a belt 64.

The operation of the apparatus shown in Fig. 2 is as follows: If it is desired to roll 20 sheet metal plates of a medium length, the main slide 6 is set in the position shown in Fig. 2. The guides 44 are set in their upper 25 positions shown in dotted lines. The guides 39 are in their lower positions shown in full lines. The blank is placed on the table 4 and brought between the reducing rolls 1 and 2. After the blank has passed between the reducing rolls it is guided by the guide strips 39 between the guide rollers 14 and 30 15. After the blank has passed between these guide rollers it is engaged between the guides 53 and 54 by means of which it is passed between the upper part of the upper reducing roll 1 and the guide rollers 61. 35 Finally the blank is fed downward by means of the guides 59 and the rollers 61 and 63, whereupon it is again passed between the reducing rolls 1 and 2 and thereafter between the guide rollers 14 and 15. This operation is repeated until the blank has been 40 reduced to the desired thickness. Now the guides 39 are set in the upper position shown in dotted lines by means of the hand levers 42, so that the blank after passing between the reducing rolls 1 and 2 is fed to and removed from the frame 34. The shafts 38 and 43 of the guides 39 and 44 are located above the horizontal line which is tangential 45 of the upper part of the lower reducing roll 2. Therefore, when the guides 39 and 44 are set in the upper positions shown in dotted lines, they permit the finished blank to be removed substantially in horizontal direction, so that the blank is not bent by 50 striking against the shafts.

If it is desired to roll short blanks, the main slide 6 is shifted to the left by means of the spindles 11, until the inner guide rollers 14 are in contact with the upper 55 reducing roll 1, as is indicated in the figure by a circle shown in broken lines. The outer guide rollers 15 are shifted to the right by means of the spindles 25, so that they are out of engagement with the rollers 14. The guides 39 are rocked upward into the posi-

tion shown in dotted lines, and the guides 44 are set in the positions shown in full lines. The guide strips 31 and the frames 34 are removed and in lieu thereof a carriage such as shown at 36 in Fig. 3 is 70 wheeled on the frame portion 3^a to a position below the slide 6. After passing between the reducing rolls 1 and 2 the blank is 75 passed around the upper reducing roll 1 by means of the guides 44, the rollers 14, the guides 57, the rollers 61, the guides 59, and the rollers 63, whereupon it is again fed between the reducing rolls 1 and 2. When 80 rolling short blanks guide rollers of smaller diameter (corresponding to the roller 65 of Fig. 3) may be provided in lieu of the upper 85 guide rollers 61. After the blank has been sufficiently reduced, the guides 44 are rocked into the position shown in dotted lines by means of the foot lever 50, so that the blank 85 is removed below the said guides and to the carriage 36.

When it is intended to roll blanks of great length the main slide 6 is, by means of the spindles 11, shifted to the right of the position it has in Fig. 2. Otherwise the rolling and feeding of the blank around the upper reducing roll is effected in the same way as the rolling and feeding of the blank of medium length which has been described 95 above.

When setting the main slide 6 the pressure of the outer guide rollers 15 on the inner guide rollers 14 and on the blank is not changed. By rotating the spindles 25 the 100 said pressure can be regulated as desired in all the positions of the slide 6.

When using the mill for polishing short or long blanks means must be provided for dressing or smoothing the upper and lower 105 reducing rolls 1 and 2. In this case the transverse bar 28 is equipped with a layer 28^a of felt which is used for dressing the lower roll 2, as is shown in Fig. 3. The upper roll 1 is dressed by means of rolls 110 63 and 65 which are covered with layers 63^a and 65^a of felt.

If rolling or polishing of short blanks is not necessary, the feeding apparatus can be constructed in the manner shown in Fig. 4, 115 which is similar to the construction shown in Fig. 2. However in the apparatus shown in Fig. 4 the guides 57 are omitted.

In the example shown in Fig. 4 the guide strips 53 and 54 secured to the transverse bars 120 7 and 8 engage with the ends which are directed to the upper part of the upper reducing roll 1 between two sets of guide strips 66 and 67 which are secured to the bearing blocks 70 of the upper roll 1 by means of 125 transverse rods 68 and 69. Furthermore laterally of the sets of strips 66 and 67 guide plates 71 are secured to the rods 68 and 69. Between the guide plates 71 guide plates 72 are located which are secured to 130

the transverse rods 7 and 8 and laterally of the sets of strips 53 and 54. When shifting the slide 6 the guide which consists of the strips 53 and 54 and the plates 72 is telescoped within the guide provided by the strips 66 and 67 and the plates 71. By the said guides the blank is securely fed to the upper part of the upper reducing roll 1 in all the positions of the slide 6. Instead of the sets of strips 53, 54, 66, and 67 plates may be provided. These plates are preferably provided with tongues which engage between the rollers 14 and 15.

Instead of a group of rollers 14 and 15 single rollers may be provided on the shafts 16 and 17 which are broader than the rollers of the groups shown in the figures.

Figs. 6 and 7 illustrate a mill in which the two rollers 14 and 15 extend over the entire width between the frames 10, and plates 53, 54, and 57 are each made of a single piece of sheet metal instead of strips as in Fig. 5, and, like rollers 14 and 15, these plates extend over the entire width between the said frames.

I claim herein as my invention:

1. In an apparatus of the class described, the combination with at least two reducing rolls, of two guide rollers located at the rear of the reducing rolls and one behind the other and with one of them adjacent to one of the reducing rolls, and means for shifting the guide roller which is adjacent to one of the reducing rolls toward and away from said reducing roll.

2. In an apparatus of the class described, the combination with at least two reducing rolls, of two guide rollers located at the rear of the reducing rolls and one behind the other and with one of them adjacent to one of the reducing rolls, and means for shifting both guide rollers toward and away from the reducing rolls and placing the roll which is adjacent to one of the reducing rolls in and out of contact therewith.

3. In an apparatus of the class described, the combination with at least two reducing rolls, of a slide located at the rear of the reducing rolls, two guide rollers mounted on said slide one behind the other and with one of them adjacent to one of the reducing rolls, and means for shifting the slide toward and away from the reducing rolls and placing the roll which is adjacent to one of the reducing rolls in and out of contact therewith.

4. In an apparatus of the class described, the combination with at least two reducing rolls, of a slide located at the rear of the reducing rolls, outer and inner guide rollers mounted on said slide one behind the other and with the inner one adjacent to one of the reducing rolls, the outer roller being yieldingly and adjustably mounted on said slide, and means for shifting the slide to-

ward and away from the reducing rolls and placing the roll which is adjacent to one of the reducing rolls in and out of contact therewith.

5. In an apparatus of the class described, the combination with at least two reducing rolls, of a slide located at the rear of the reducing rolls, outer and inner guide rollers mounted on said slide one behind the other and with the inner one adjacent to one of the reducing rolls, a spring acting on the outer roller and tending to force the same in contact with the inner roller, a set screw acting on said spring and adapted to regulate the tension thereof, and means for shifting the slide toward and away from the reducing rolls and placing the roll which is adjacent to one of the reducing rolls in and out of contact therewith.

6. In an apparatus of the class described, the combination with at least two reducing rolls, of two guide rollers located at the rear of the reducing rolls and one behind the other and with one of them adjacent to one of the reducing rolls, means for shifting the guide rollers toward and away from the reducing rolls and placing the roll which is adjacent to one of the reducing rolls in and out of contact therewith, and means for guiding said guide rollers when shifting them.

7. In an apparatus of the class described, the combination with at least two reducing rolls, of a slide located at the rear of the reducing rolls, two guide rollers mounted on said slide one behind the other and with one of them adjacent to one of the reducing rolls, means for shifting the slide toward and away from the reducing rolls and placing the roll which is adjacent to one of the reducing rolls in and out of contact therewith, and means for guiding said guide rollers when shifting them.

8. In an apparatus of the class described, the combination with at least two reducing rolls, of two guide rollers located at the rear of the reducing rolls and one behind the other and with one of them adjacent to one of the reducing rolls, means for shifting the guide roller which is adjacent to one of the reducing rolls toward and away from said reducing roll, and movable guide members located at the rear of the reducing rolls and adapted to be set in positions for directing the blank being rolled from the reducing rolls between the reducing roll and adjacent guide roller, between the guide rollers, and away from the roll train.

9. In an apparatus of the class described, the combination with at least two reducing rolls, of two guide rollers located at the rear of the reducing rolls and one behind the other and with one of them adjacent to one of the reducing rolls, means for shifting the guide roller which is adjacent to one of the

reducing rolls toward and away from said reducing roll, and movable guide members located at the rear of the reducing rolls and adapted to be set in positions for directing the blank being rolled from the reducing rolls between the reducing roll and adjacent guide roller, between the guide rollers, and away from the roll train, said guide members being arranged in such positions that

they can be moved out of the path of the 10 blank coming from the reducing rolls.

In testimony whereof I have signed this specification in the presence of two subscribing witnesses.

ANASTASIUS MÄUSEL.
